UNITED STATES PATENT OFFICE.

HENRY A. KEINER, OF BROOKLYN, NEW YORK, ASSIGNOR TO ELIZABETH C. SEAMAN, OF NEW YORK, N. Y.

DESIGN FOR A HANDLE.

SPECIFICATION forming part of Design No. 35,650, dated February 4, 1902.

Application filed October 7, 1901. Serial No. 77,918. Term of patent 14 years.

To all whom it may concern:

Be it known that I, HENRY A. KEINER, a citizen of the United States, residing in the borough of Brooklyn, city of New York, county of Kings, and State of New York, have invented and produced a new, useful, and original Design for Handles, of which the following is a specification.

The leading feature of my design is a tubular handle having a tubular grip, and projecting from each side of the grip is an inwardly-dished arm closing the open end of the tubular grip.

In the accompanying drawings I have illustrated a handle showing an embodiment of my design.

In the drawings, Figure 1 is a side view of the handle. Fig. 2 is a plan view thereof. Fig. 3 is a section on line 3 3 of Fig. 1; and Fig. 4 is a section on line 4 4 of Fig. 1, clearly showing the recess c.

In the drawings, *a* indicates the tubular grip. Projecting in the same general direction from each end of the grip are arms *b*. These arms *b* are dished inwardly throughout substantially their entire length to form the recess *c* to obstruct the open end of the grip and to form concave edges at the junctions of the arms with the grip. Projecting laterally from the dished arms are ears *e*.

What I claim is—

The design for a handle substantially as herein described and shown in the drawings.

In testimony whereof I have signed my name to this specification, in the presence of two subscribing witnesses, this 28th day of September, 1901.

HENRY A. KEINER.
